UNITED STATES PATENT OFFICE.

FRANK E. ELLIS AND ROBERT A. HASSELBACH, OF REVERE, MASSACHUSETTS.

CLIP FOR WEB-PRESS PLATE-CYLINDERS.

No. 893,990.

Specification of Letters Patent.

Patented July 21, 1908.

Application filed March 5, 1908. Serial No. 419,310.

To all whom it may concern:

Be it known that we, FRANK E. ELLIS and ROBERT A. HASSELBACH, of Revere, in the county of Suffolk and State of Massachusetts, 5 have invented certain new and useful Improvements in Clips for Web-Press Plate-Cylinders, of which the following is a specification.

This invention relates to means for securing 10 the printing plates to the plate cylinders of web presses, that is, of presses of that type which print newspapers upon a continuous web of paper. With presses of this character the type plates are curved cylindrically 15 to fit upon rotating cylinders, and are secured by clips which engage the opposite ends of the plates. The end edges of the plate are beveled off and the clips are undercut so as to overlap the beveled edges and prevent removal of the plate.

It has been the practice hitherto to provide fixed clips to engage one end of each plate, and movable clips to engage the other end, there being three or more of such movable 25 clips to act upon each plate. These clips have always been independently mounted, and each has had an independent actuator by which to clamp it against the plate. This consequently has necessitated independent 30 adjustment of all the clips, and has resulted in making practically impossible a uniform engaging pressure by all the clips. In adjusting these clips it has been the universal practice to move each of them up into contact 35 with the plate without bringing any great pressure to bear, and then applying an additional twist to the adjusting screw of each clip to clamp it firmly. The pressure thus applied is made as nearly equal as can

40 be in the limited time at the disposal of the workman, and in the absence of any device for measuring the pressure, but it depends altogether on the judgment of the workman whether the clips do actually have the same 45 degree of tightness or not. Indeed, it often happens that a slight extra pressure is given to the last clip, which has the effect of springing the plate. A sprung plate is one of the defects most to be avoided in the operation 50 of printing presses of this character, for it not only prevents a perfect impression being made, but also breaks the web of paper.

It sometimes happens that plates before being applied to the cylinder are sprung out 55 of the truly cylindrical form, and when thus defective, their defect is not remedied, but

rather accentuated by the employment of the separate independently adjustable clips, for if each of these clips is individually adjusted with equal force against the plate, there is no latitude given for the plate to be sprung back into proper shape by the printing pressure, and there is no way for the workman to tell which of the clips it is necessary to leave slightly loose to permit of this re-shaping of the plate.

The object of our invention has been to devise a clip which could be adjusted and clamped against the printing plate by a single actuator in one operation, and which would engage practically the entire end of the plate with a uniform pressure.

It is also our object to arrange the engaging edge of our clip in such a way that it would bear a constant angular relation to the printing plate, and be accurately positioned against the latter, whether the plate may have been previously sprung or not, thereby engaging only the properly-formed parts of the plate and allowing the distorted portion 80 latitude for returning to its correct form.

A clip of this character is illustrated in the accompanying drawings, in which,—

Figure 1 represents an elevation of one end of a plate cylinder having our invention applied thereto. Fig. 2 represents a longitudinal section of such a cylinder. Fig. 3 represents a combined end elevation and cross-section of such a cylinder.

The same reference characters indicate the 90 same parts in all the figures.

1 represents a printing-plate cylinder of the kind usually used in web printing presses, such a cylinder carrying ordinarily four printing plates 2 which are arranged end to end 95 and side by side, that is, each plate covering approximately half the circumferential surface of the cylinder and somewhat less than half of its length. The printing plate is beveled at the opposite end edges 3 and 4, as appears in Fig. 1, so as to engage under the undercut edges of holding clips provided to secure the plate in place. One of the ends of the plate is secured by the fixed clips 4' which are attached in any manner so as to be 100 permanent, to the cylinder midway between its ends, and are undercut on the opposite sides. The end of the printing plate nearest the cylinder end is engaged by a movable clip 5. This clip is a curved metal band or 110 strip which is concentric with the cylinder 1 and printing plate 2, and is movable longitudi-

dinally of the cylinder into and out of engagement with the printing plate. The clip near its central portion is rigidly connected with a projection 6 which has lateral wings 5 projecting into the undercut sides of a groove 7 extending longitudinally of the cylinder. This projection 6 is therefore enabled to slide horizontally in this groove. It is connected with the clip either by being made 10 integral therewith or secured in any other sufficiently permanent manner.

On each side of the projection or central slide 6 are other slides 8 and 9 which fit in correspondingly formed grooves or guide- 15 ways 10 and 11. The end portions of the clip are detachably secured to the slides 8 and 9 by suitable securing means, such as the screws 12 and 13.

There is a single actuator for the clip con- 20 sisting of a screw 14 contained within the groove 7 having its inner end contained in a bearing in the body of the cylinder, and its outer end passing through a plate 15 secured to the cylinder. A collar 16 bearing against 25 the inner side of the plate prevents endwise movement of the screw. This screw is threaded through the slide 6 and has its outer end 17 squared to receive a wrench.

It will be noted that by reason of the rigid 30 connection of the clip 5 with the central slide, and its attachment to the end slides 8 and 9, the single actuator 14 is enabled to advance the clip bodily, and all three slide simultaneously therewith toward and from the 35 adjacent end of the printing plate, and to maintain the engaging edge of the clip parallel to itself in all positions. Thereby rotation of the screw 14 alone is sufficient to bring all parts of the clip into engagement 40 with the printing cylinder. This clip is of sufficient length to extend almost as far as the plate itself, so that it engages over nearly or practically the entire end of the plate, and secures the same as efficiently as was done 45 previously by the three independent clips. By reason of this single actuator, much time in securing the plates is saved, and the pressure applied is equal throughout the extent thereof. The same construction enables a 50 plate which is warped or otherwise distorted to be properly clamped and made to conform to the surface of the cylinder, for the fact that the clip engages the plate over a considerable distance and bears against it 55 with equal pressure at its ends, being at the same time undercut so as somewhat to overlap the beveled end of the plate, causes the plate to be pressed down against the cylinder evenly at its ends. When separate clips are 60 used to engage the plate at separated points, there is liability for any distortion of the plates to be increased, because of the fact that the clips are independently screwed up against it, and that it is difficult or impossi- 65 ble to apply equal pressure with all of the

clips. With our improvement, this tendency is avoided, and the opposite effect secured.

It will be noted in Fig. 1 that the active edge of the clip is somewhat concaved, being 70 recessed slightly between its ends on a curve of large radius extending nearly from one end to the other. This causes the ends of the clip to be slightly in advance of the center and to engage the plate first, thereby 75 more accurately positioning and more securely holding the same than would be the case if the central part engaged first. The elasticity of the clip allows the ends to spring slightly until substantially the entire 80 engaging edge of the clip bears against the plate.

The parts above described are duplicated in the form of plate cylinder here shown, where independent printing plates are mounted upon opposite sides of the cylinder. Each clip extends nearly half way around the circumference of the cylinder. 85

We claim:—

1. In combination with a plate cylinder, a 90 plurality of slides mounted to travel longitudinally thereon, a bowed clip connected to said slides arranged to engage and secure the end of a printing plate to the cylinder, and a single actuator for moving the clip and slides 95 simultaneously toward and from the plate.

2. In combination with a plate cylinder, three slides mounted in longitudinal undercut guideways in the surface of the cylinder, a clip secured at its ends and middle respec- 100 tively, to all three slides having one edge shaped to fit the beveled edge of a printing plate and secure the same to the cylinder, and a single actuator acting on the middle slide to move all the slides and the clip simultaneously and equally toward and from the 105 plate.

3. The combination with a plate cylinder of a cylindrically curved printing plate adapted to fit the surface of said cylinder and beveled off at its ends, a clip consisting of a plate also curved concentrically with the cylinder and undercut on the edge adjacent to said plate so as to fit over the beveled edge thereof to secure the same to the cylinder, 110 said clip being substantially co-extensive with the printing plate so as to engage the latter at points close to the opposite side edges thereof, a plurality of slides to which said clip is connected, and a single actuator 115 for moving said clip into and out of engagement with the printing plate.

4. The combination with a plate cylinder of a cylindrically curved printing plate adapted to fit the surface of said cylinder and beveled off at its ends, a clip consisting of a plate also curved concentrically with the cylinder and undercut on the edge adjacent to said plate so as to fit over the beveled edge thereof to secure the same to the cylinder, 125 130

said clip being substantially co-extensive with the printing plate so as to engage the latter at many and widely-separated points, a T-shaped slide member projecting from the 5 clip and fitting in an undercut groove in the cylinder, slides similarly mounted detachably secured to the opposite ends of the clip; and a single actuator for moving said clip into and out of engagement with the printing 10 plate.

5. In combination with a plate cylinder and a curved printing plate fitting thereon, a plurality of slides having attached means for

engaging the edge of the plate and securing it to the cylinder, and a single screw operatively engaged indirectly with all of said slides through said attached means, for bringing the same simultaneously against the plate at a plurality of widely separated points. 15

In testimony whereof we have affixed our 20 signatures, in presence of two witnesses.
